(57) **CLAIM**

The ornamental design for a combination construction layout and conduit bending tool, as shown and described.

DESCRIPTION

FIG. 1 is an upper front-left perspective view of the combination construction layout and conduit bending tool.

FIG. 2 is a front view of the combination construction layout and conduit bending tool.

FIG. 3 is a rear view of the combination construction layout and conduit bending tool.

FIG. 4 is a left side view of the combination construction layout and conduit bending tool.

FIG. 5 is a right side view of the combination construction layout and conduit bending tool.

FIG. 6 is a top view of the combination construction layout and conduit bending tool.

FIG. 7 is a bottom view of the combination construction layout and conduit bending tool; and,

FIG. 8 is a lower front-left perspective of the combination construction layout and conduit tool.

1 Claim, 8 Drawing Sheets
